UNITED STATES PATENT OFFICE.

NORMAN TATHAM, OF LOS ANGELES, CALIFORNIA.

DESIGN FOR A SCALE CASING.

Application filed May 28, 1928. Serial No 26,892. Term of patent 7 years.

To all whom it may concern:

Be it known that I, NORMAN TATHAM, a citizen of the United States, residing at Los Angeles, in the county of Los Angeles and State of California, have invented a new, original, and ornamental Design for a Scale Casing, of which the following is a specification, reference being had to the accompany-

ing drawing, forming part thereof.

The figure is a perspective view of a scale casing, showing my new design.

I claim:

The ornamental design for a scale-casing, as shown.

NORMAN TATHAM.
